United States Patent Office

Des. 234,203
Patented Jan. 28, 1975

234,203

BLOWER

Gunter Wrobel, Villingen, Black Forest, Germany, assignor to Papst-Motoren KG, St. Georgen, Schwarzwald, Germany

Term of patent 14 years

Int. Cl. D23—04

U.S. Cl. D23—162

Fig. 1

Fig. 2

Fig. 3

Fig. 4

FIG. 1 is a side elevational view of a blower showing my new design.

FIG. 2 is a top plan view thereof.

FIG. 3 is an elevational view as seen from the left side of FIG. 2.

FIG. 4 is a front top and left side perspective view. The rear of the blower is flat and unornamented.

I claim:

The ornamental design for a blower, as shown and described.
